UNITED STATES PATENT OFFICE.

EDWARD H. COOPER, OF FOND DU LAC, WISCONSIN, ASSIGNOR OF ONE-HALF TO FRANK M. GIVENS, OF SAME PLACE.

HORSE-COVER.

SPECIFICATION forming part of Letters Patent No. 518,838, dated April 24, 1894.

Application filed July 24, 1893. Serial No. 481,296. (No model.)

To all whom it may concern:

Be it known that I, EDWARD H. COOPER, of Fond du Lac, in the county of Fond du Lac and State of Wisconsin, have invented a new and useful Improvement in Horse-Covers, of which the following is a specification.

My invention is an improvement in horse covers and consists in the special features of construction and novel combinations of parts 10 as will be hereinafter described and pointed out in the claim.

In the drawings—Figure 1 is a perspective view of a blanket provided with my improvements. Fig. 2 is a side view of my girth hook and Fig. 3 is a section thereof on about line 3—3 of Fig. 2.

The cover A may be of blanketing jute or other material desired and is provided at one side of its front lower edge with a ring B and 20 at its other side with a series of rings C and also with a strap D which has at its free end a snap hook d. It is also preferred to stitch or otherwise secure a sufficient length of said strap D to the cover to form a support for 25 the rings C the latter being secured to the strap as shown. In use the snap hook d is carried through the ring B returned and caught into any desired one of the rings C to properly secure the blanket.

30 To the blanket between its ends is secured one end of the girths E the opposite ends of which are supplied with the girth hooks F constructed as presently described and to the blanket opposite these girth I secure the 35 loops G for engagement by the hook. These loops are preferably formed from leather straps as shown as the friction afforded thereby aids in preventing the detachment of the hook.

40 The girth hooks F are alike being formed with the frame 1 having the cross bars 2 and 3, the top bar 4, loop or keeper 5 and the hook proper 6. The cross bars 2 and 3 are arranged in the same plane and in a common 45 plane with the opening 7 in the keeper 5 so that the girth strap passed up through the keeper around the cross bars and back and through the keeper will be pressed firmly upon itself to lock securely without the necessity of a fastening tongue and so that the 50 strap can be conveniently adjusted as may

be desired. The arrangement of the opening in the keeper in the same plane as the cross bars of the frame is an important feature in accomplishing the locking of the strap 55 as it brings the strap lengths close together and holds them in such relation after they

leave the lower cross bar of the frame, avoiding all danger of the strap slipping. The hook proper 6 extends the full width of the 60 frame in a straight line at right angles to the length of said frame and forms a square bearing to fit in the strap loop. At its free end the hook proper projects laterally beyond the frame and is inclined rearwardly forming 65 an inclined wing 8 projecting from the end of the hook proper and aiding in guiding the hook into the loop and in securing it from accidental displacement when engaged with the said loop.

By means of this lateral inclined wing 8 the hook can be applied to the loop even if the girth be drawn as tight as it is desired to use it the inclination of the wing 8 bringing its point, when the hook is turned to one side to position to enter one 75 side of the loop when the hook may be easily slipped thereinto and may also be removed by a reversal of said operation.

In applying the blanket to the horse it will be seen the front fastening operates to permit a proper fitting of the blanket at the front of the animal and also permits the blanket to be drawn closely to the animal at such point or left loose as may be desired according to the weather, the hook fastening aiding in such 80 adjustment by securing the blanket by what may be termed a fixed adjustment upon the blanket. By this I mean that being once adjusted to the animal's girth it may be left fixed and there is practically no straining in 85 fastening the hooks so that whether the front fastening be tight or loose the front is not disarranged by the fastening or unfastening of the girth hooks.

Having thus described my invention, what 90 I claim as new, and desire to secure by Letters Patent, is—

In a horse cover as an improved article of manufacture the girth hook herein described having at one end the hook proper having 95 the cross bar provided at one end with the extension or wing projected laterally beyond

the side of the hook and inclined rearwardly as described, and having its opposite end provided with a loop or keeper the opening of which is arranged in the plane of the hook 5 and provided above said loop with a plurality of cross bars arranged in a common plane and in a plane with the opening in the lower

oop or keeper all substantially as and for the purposes set forth.

EDWARD H. COOPER.
